TROPHY FIGURINE

Angelo Pane, Chicago, Ill., assignor to General Classics, Inc., a corporation of Illinois

Filed May 24, 1962, Ser. No. 70,256

Term of patent 7 years

(Cl. D29—23)

FIG. 1 is a side elevational view of a trophy figurine embodying my new design;

FIG. 2 is an end elevational view thereof;

FIG. 3 is a top plan view thereof with the broken line showing of the car omitted for convenience of illustration; and

FIG. 4 is a bottom plan view of the trophy figurine.

The side and end not shown are substantially the same as the side and end shown.

The essential features of my design reside in the portions shown in solid lines.

I claim:

The ornamental design for a trophy figurine, substantially as shown and described.
